UNITED STATES PATENT OFFICE.

JAMES P. BURKE, OF STRUTHERS, OHIO.

FASTENING DEVICE FOR CARDS, CALENDARS, &c.

1,328,123.

Specification of Letters Patent.

Patented Jan. 13, 1920.

Application filed April 10, 1919. Serial No. 288,980.

To all whom it may concern:

Be it known that I, JAMES P. BURKE, a citizen of the United States, and a resident of Struthers, in the county of Mahoning 5 and State of Ohio, have invented a new and Improved Fastening Device for Cards, Calendars, &c., of which the following is a full, clear, and exact description.

This invention relates to fastening devices 10 and has particular reference to pins, thumb tacks or analogous devices employed for the purpose of fastening cards, pictures, signs, calendars or other analogous light thin bodies to supports such as walls, window frames, or the like for display, exhibition or 15 other purposes. The device of whatever character to be supported will be referred to hereinafter for convenience of description as a card.

20 Among the immediate objects of this invention is to provide a card holder or fastening device so constructed as to occupy a minimum amount of space in idle position and which in such position carries the pin or 25 sharp pointed portion in shrouded or guarded position so that the devices may be handled in large quantities with absolute immunity.

Another object of the invention is to provide 30 a card fastening device having any suitable means for attachment to the card, but having specially designed fastening point with a coöperating finger piece through which the operator may easily insert the 35 sharp point into the wall for reliable holding purposes.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to 45 the accompanying drawings, in which like reference characters designate the same parts in the several views, and in which—

Figure 1 is a front elevation of one form 50 of my device shown in operative position and holding a card against the wall.

Fig. 2 is a side elevation of the same and indicating the wall or other support in vertical section on the line 2—2 of Fig. 1.

Fig. 3 is a plan view of the device in normal flat form.

Fig. 4 is a side or edge view of the same; and

Figs. 5, 6 and 7 are detail views of modified forms of card attachment means for the lower ends of the fastening devices. 60

Referring now more specifically to the drawings I show my improved fastening device as being formed as by stamping from a piece of sheet metal or the like and comprising a body 10 having at one end any suitable 65 card securing means such as tongues 11 bendable around bending lines 11' for projection through slits 12 in a card or the like and then bendable against the rear face of the card as indicated in dotted lines in 70 Fig. 1. Obviously other forms of securing means may be substituted and for which I make no claim *per se* in this specification. In Fig. 5 the card holding means comprises a tongue 11^a foldable upward against the 75 body of the device and having card gripping teeth 13 at its upper edge. In Fig. 6 the tongue 11^b is struck outward from the body of the device leaving a rim 14 which together with the main portion of the body 80 will lie flat against the face of the card while the tongue being bent upward against the back of the card will make a rigid lock. In Fig. 7 the tongue 11^c is similar to that in Fig. 5, but has a smooth edge portion 15. 85 These are only a few of many card holding means that might be employed.

16 indicates an integral extension on the upper end of the body 10 which will serve as a finger piece in the manipulation of the 90 fastening device in the attachment to the wall or removal of the card therefrom. This finger piece may be perfectly flat or as indicated in Figs. 1 and 2 may have its point or tip somewhat rounded as shown at 16'. In 95 its normal form the finger piece constitutes a flat extension of the body 10 but may easily be bent into a right angle with the body around the horizontal bending line 17, which being the weakest part of the body as 100 will presently appear, facilitates this bending action, although I prefer to score the metal as indicated at 17' slightly during the stamping action to facilitate the bending of the finger piece and so make a substantially 105 square bend or corner.

In the stamping operation the triangular portion 18 of the metal is stamped out free from the body 10 along two longer sides 19 which constitute in geometrical language in 110

the form illustrated the two sides of an isosceles triangle whose base is the bending line 17. The metal 18 struck out from this triangular opening of the body remains as an 5 integral part of the finger piece and lies always substantially in the same plane thereof. This metal portion 18 is formed in any suitable manner into a sharp pointed pin 20 shown in this instance as being twisted or 10 otherwise formed with a spiral surface somewhat like a gimlet point and which when the finger piece and the point are bent into the position at right angles to the body 10 may be turned or otherwise forced readily into 15 the wall 12 by grasping the finger piece, the card C in the meantime having been secured to the body 10. Obviously I do not propose to be limited to any specific formation of the opening in the body 10 for the making of 20 the pin nor to any particular finish of the surface of said pin. The form of the pin shown, however, is possessed of maximum strength and while it may easily be turned or screwed into the wall will hold most ef- 25 ficiently therein in practice.

I claim:

1. The herein described card fastening device comprising a body of flexible material, means to secure a card to the body, a finger piece integral with the body and bendable from the plane of the body in a position at an angle thereto, and a wall engaging member integral with the finger piece and movable therewith with respect to the body. 30
35. 2. The herein described card holder comprising a body of flexible material, means to secure a card thereto, a finger piece formed integral with the body and bendable along a transverse line so as to occupy a position at an angle to the body, and wall engaging means formed integral with the finger piece and struck from the body in the formation of the device, said wall engaging means lying always substantially in the same plane 40 as the finger piece and being swung thereby into wall engaging position simultaneously with the bending of the finger piece from the plane of the body. 45
50. 3. In a card fastening device, the combination of a body of flexible material, means to secure a card thereto, the body having an

opening formed therein, a finger piece having integral connection with the edge portions of the body and bendable into an angle with the body around a transverse bending 55 line at one end of the said opening, and a wall engaging member constituting an integral part of the finger piece and formed from the material removed from the opening and bendable with the finger piece into 60 wall engaging position.

4. In a fastening device for cards, the combination of a body of flexible material, card engaging means carried thereby, the body being provided with a central triangular 65 opening the apex of which is directed toward the card engaging means, a finger piece constituting an extension of the body and bendable into a position at an angle thereto around a line constituting the base of said 70 triangular opening, and a wall engaging point formed from the material struck from the triangular opening and constituting an integral extension from the finger piece.

5. In a device of the character set forth, 75 the combination of a body of flexible material, a finger piece connected to one end thereof and bendable around a weakened line into a position at right angles to the body, and a wall engaging pin carried by the 80 finger piece and movable into wall engaging position simultaneously with the bending of the finger piece aforesaid, said pin being guarded by the body in normal inoperative position of the device. 85

6. In a card fastening device, the combination of a body of flexible material, a finger piece formed as an integral part thereof and bendable around a weakened line into a position at an angle thereto, said body having 90 formed along its longitudinal center a triangular opening, and a wall engaging point formed from the material removed from the opening and having integral connection with the finger piece at the base of the triangular opening, the pin being formed with a sharp point and reinforced shank due to the width of the base aforesaid, and having 95 means on its surface to prevent accidental release of the device from the wall.

JAMES P. BURKE.
